UNITED STATES PATENT OFFICE

2,042,196

SCARIFIER

Nicholas H. Senz, Portland, Oreg.

Application June 1, 1934, Serial No. 728,510

5 Claims. (Cl. 37—145)

My invention relates to scarifiers adapted to be attached to what is known as a bulldozer machine which is a powerful tractor of the caterpillar type having an adjustable grader blade 5 at one end for road making.

Such machines have enormous tractive power and a very considerable problem presents itself in making attachments such as grader blades and scarifiers that will have the requisite strength 10 without objectionable weight, it being expedient to use the best alloy steels in any event.

The purpose of my invention is to combine the grader blade and the scarifier in such a manner:—

15 First, that the strength of one member will support that of the other and whereby each may be made lighter than would otherwise be necessary;

20 Second, to so distribute the material of construction in thus combining the two elements that each will utilize as far as possible the material and distribution of both according to the well understood principles of stress resistance;

25 Third, to so attach the scarifier teeth that they are securely held yet easily removable; and

Fourth, to so arrange the scarifier that the teeth may be projected a short distance to engage a hard road surface and when thus projected to be supported intermediate their length and thus 30 greatly strengthened.

With these and other objects which will be apparent to those skilled in the art to which this invention appertains, my invention resides in the parts and combinations of parts and structures 35 hereinafter described in this specification and delineated in the accompanying drawing, in which,—

Fig. I is a back view broken in two to avoid 40 undue length of the drawing and repetition of the parts;

Fig. II is a section on the line II—II of Fig. I and shows the scarifier teeth in their retracted or inoperative position; and

45 Fig. III is a fragmentary view of the lower portion of Fig. II, showing the scarifier teeth in the position that they will occupy when practically fully extended.

It will be understood that the scarifier teeth 50 may occupy any intermediate position between that shown in Fig. II and Fig. III and that at all times the back of the scarifier teeth will be supported as hereinafter explained.

The tractor, its operating parts and means for 55 attaching the blade and the scarifier to the

tractor are not shown as they are well understood and form no part of the present invention.

My device consists essentially of the grader blade 1, which as explained will be suitably attached to the tractor with provision for adjustment as to depth of cut and angularity of blade with respect to the roadway in the known manner. An angular support 2, is attached to the back of the blade 1 at 3c in a secure manner, 5 preferably by fusion welding or equivalent means. 10

Attached to the support 2 is a trough 3, preferably made of structural steel plate formed to define three sides of a quadrangle and which will extend substantially the length of the blade from 15 end to end as shown in Fig. I.

Movable vertically in the trough 3, is a scarifier beam 4, having a plurality of pockets 5 within which are placed the scarifier teeth 6, a counter bore 7, in the beam 4, accommodates the head 8, of the scarifier teeth 6. A plate 9, preferably of 20 steel, serves as a retainer for holding the scarifier teeth against being driven out of the beam 4 under conditions of use. The plate 9 is held by a plurality of studs such as 10, each of which is provided with a slot 11, within which is driven 25 a taper key 12. A hydraulic cylinder 13 is positioned above the plate 9 and is equipped with a piston rod 14 and in the interior is a piston which is not shown, the details of hydraulic cylinders 30 needing no explanation to those familiar with such machines. Pipes 15 and 16, provide means for ingress and egress of hydraulic fluid to the cylinder 13, and a control, not shown, will be provided to operate this cylinder and its piston in 35 the known manner.

Large tractors of the character used for this machine are always provided with hydraulic pumps, using oil as a hydraulic medium, for manipulating the various parts and particularly 40 for raising, lowering and swinging the grader blade; hence no additional equipment will be required to operate my new scarifier.

It will be noted that the trough 3, is a hollow beam well adapted to develop great strength in 45 proportion to the amount of material used in its construction; that it contains a substantially solid beam 4, preferably made from a steel casting, tough, resilient and of great strength and having a high elastic limit.

It will be noted that the angular support such 50 as 2 will be another hollow beam provided with a plurality of webs such as 2a intended to develop the greatest strength possible for the amount of material used and it will be also noted 55

that it supports the tip of the blade 3a close to its working edge.

One of the most important features of my new device is the series of slots 3b, through which the scarifier teeth project and as shown in Fig. III they support the scarifier teeth 6 in such a manner that there is ordinarily no leverage pressure at the point where they emerge from the beam indicated by 4a. Consequently when it is desired to plow up a pavement such as macadam, substantially as hard as cement concrete, these teeth may be projected by using the hydraulic cylinders to give a very small degree of penetration. The teeth 6 will be supported from close to their points and being made of the best material obtainable, they will tear up a pavement of the character indicated and utilize to a full extent the enormous power available from a driving mechanism of the character heretofore indicated. On a second trip and when the extremely hard surface of the pavement has been broken up the teeth may be extended to their full extent about as shown in Fig. III, or a little further, and the balance of the roadway completely broken up. Upon withdrawal of the scarifier teeth 6 to the position shown in Fig. II the grader blade 1 may be placed in service in the customary manner very effectively supported by the scarifier and its structural elements.

I am aware that blade graders are old; I am also aware that scarifier attachments both adjustable and fixed are old in the art but I am not aware that the blade and the scarifier attachment have heretofore been combined in my effective manner and I am not aware that provision has ever been made to support a scarifier tooth intermediate its length of projection from a scarifier beam in such a manner and so effectively as I have done it and for the purpose indicated.

Having thus fully described my invention so clearly and completely that those skilled in the art to which it appertains, or is most nearly connected, may make and use the same without further information; it being understood that

variations may be made within the scope of the appended claims, what I claim as new and desire to secure by Letters Patent, is,—

1. In a scarifier for a grader, a grader blade, a support on the back of the blade that is rigid therewith, a hollow beam member rigid with the support and a scarifier head adjustably movable vertically within said hollow beam. 5

2. In a blade type grader, a blade, a box-like beam on the back of the blade that is rigid therewith, a scarifier head adjustably movable within the said hollow beam, hydraulic means for controlling the scarifier head, scarifier teeth in the said head and slots in the bottom of the hollow beam through which the teeth are adapted 15 to project.

3. In a scarifier attachment for a grading machine, a grader blade, a scarifier rearwardly of the blade and rigid therewith in horizontal planes but movable in a vertical plane, a hollow beam 20 member rigid with said blade within which said scarifier is restrained against horizontal movement and means for moving said scarifier in vertical planes to adjust for use.

4. A scarifier of the character described including a hollow beam support that is relatively fixed and a scarifier head that is movable within said beam, teeth in said scarifier head, pockets within the head for accommodation of the teeth, a plate detachably attached to the top of the 30 beam to retain the teeth within said pockets and hydraulic means attached to said plate that are adapted to move the head, plate and teeth as a unitary structure. 25

5. In a scarifier attachment for a blade-grad- 35 ing machine, a blade, a scarifier beam support made rigid with the back of the blade and ar- ranged to lend support thereto, a hollow beam made rigid with the support, a scarifier head movable within said hollow beam for vertical ad- 40 justment, teeth in the scarifier head and slots in the bottom of the hollow beam through which the said teeth are adapted to be adjustably pro- jected.

NICHOLAS H. SENZ. 45
